UNITED STATES PATENT OFFICE

160,502

MEDALLION HOUSING FOR AN AUTOMOBILE HOOD

Henry T. King, Detroit, Mich.

Application April 7, 1950, Serial No. 9,027

Term of patent 7 years

(Cl. D14—18)

To all whom it may concern:

Be it known that I, Henry T. King, a citizen of the United States, residing in the city of Detroit, county of Wayne, and State of Michigan, have invented a new, original, and ornamental Design for a Medallion Housing for an Automobile Hood, of which the following is a specification, reference being had to the accompanying drawing, forming part thereof, in which:

Fig. 1 is a front elevational view of a medallion housing for an automobile hood, showing my new design;

Fig. 2 is a top plan view thereof; and

Fig. 3 is a side elevational view thereof.

The characteristic features of my design reside in the portions shown by means of full lines in the drawing; the broken line portion of Figure 1 being merely illustrative of a medallion carried by the novel medallion housing.

I claim:

The ornamental design for a medallion housing for an automobile hood, substantially as shown and described.

HENRY T. KING.
